UNITED STATES PATENT OFFICE.

WILLIAM K. DANIELS, OF PEABODY, MASSACHUSETTS.

IMPROVEMENT IN ROTARY PRESSES.

Specification forming part of Letters Patent No. 170,436, dated November 30, 1875; application filed August 2, 1875.

To all whom it may concern:

Be it known that I, WILLIAM K. DANIELS, of Peabody, in the State of Massachusetts, have invented certain Improvements in Rotary Presses; and I do hereby declare that the following, taken in connection with the drawings which accompany and form part of this specification, is a description of my invention sufficient to enable those skilled in the art to practice it.

My improvements relate to a special construction and arrangement of certain parts of the press with a view to a more efficient pressing out and separating the moist or liquid portion from the solid matter, as, for instance, in pressing tan to render it fit for fuel; and they consist, primarily, in placing the three rolls, which do the feeding, squeezing, and discharging, in such positions and differing relative proximities to each other, as hereinafter described, as not only to insure an even feeding in, but also a forcing of the material so fed over a bridge, and then upward between pressure-rollers, and away from the expressed liquid, which passes downward and backward of the lower of the pressure-rollers, and falls away by gravity. They further consist in combining with a feeding roller a roller having longitudinal corrugations or grooves for securing an even feed, and also transverse scores, either straight or spiral, to allow the free escape of liquids between such roll and the bridge.

Figure 1 represents a central transverse section; Fig. 2, one end, and Fig. 3 the other end, of a machine embodying my invention; Figs. 4, 5, 6, 7, and 8, different forms of feeding-in rolls; and Figs. 9 and 10 styles of bridge.

A is the frame, and B the hopper, of the press. The rolls are shown in Fig. 1 at C, D, and E, and as seen they are so disposed that lines drawn from the axis of either to the axes of the others would form nearly an equilateral triangle. The feed-roll D has the smallest diameter, the delivery-roll E the next, and compressing-roll C is made the largest, whereby, while in conjunction with both the others in the acts of feeding and of squeezing, it shall also permit a wide enough separation of D from E, not only to afford space for the passage of the material over the bridge F, and

also an open space, g, between the bridge and E for the free escape by gravity of the liquid expressed by the rolls, but also shall leave ample space between its periphery and the top of the bridge F for the unimpeded passage of the material, for it will readily be perceived that there must be distance enough between D and B for the bridge and for the escape of that portion of the liquid first expressed by C and D; that if C were relatively smaller it would sink too far into this space, and would not only obstruct the passage of the material, but would require that the bridge be placed too low for efficient action, and would also require too much lift to be given to the material before being passed through between C and E. The roll D being the smallest, and the three rolls occupying the triangular position above named, a small space is left between C and D, while C and E are closer, and almost in positive contact. This leaves space for feeding between C and D, and compels a positive nipping action between C and E.

H is a chute or spout, down which the pressed material is passed after leaving the pressing-rolls.

The rolls C D E have each the same surface velocity, and they are driven by appropriate gears *i k l*, the roll D by means of its gear *k* imparting motion to the others, and itself receiving its motion from the large gear *m* on its opposite end, through the medium of the pinion *n* on the short shaft-gear *o*, which is driven by the pinion *p* on the shaft *q* of the driving-wheel *r*. The journals of rolls C are mounted in boxes *s*, which are borne down by rubber or other springs *t*, the pressure being adjustable by means of screws *u*.

My press is adapted for pressing liquids from whole, ground, or granulated substances, say for brewers', distillers', chemists', and druggists' use.

I claim—

1. In a machine for expressing liquids from solids the combination, with the bridge F, of a feeding-in roll or rolls constructed with longitudinal grooves or corrugations, serving to force and keep an even feed, and with transverse or spiral scores or grooves, serving to

allow the escape of the expressed liquids between the rolls and bridge, substantially as shown and described.

2. In a machine for pressing liquids from moist or wet substances, the combination with the solid bridge N, located as described with reference to the feeding-roll D, and to the lower discharging-roll E, of the rolls C, D, and E, having the described relative differences in

circumference, and the described relative position of their axes, but having each the same surface velocity when in action, all as and for the purposes set forth.

WILLIAM K. DANIELS.
